PLANT TRANSPLANTER

Norman G. Carlson, 2431 S. Shore Blvd.,
White Bear Lake, Minn. 55110

Filed Sept. 30, 1970, Ser. No. 25,283

Term of patent 14 years

Int. Cl. D8—01

U.S. Cl. D8—7

Fig. 1

Fig. 2

Fig. 3

Fig. 4

FIG. 1 is a front view of a plant transplanter showing my new design;

FIG. 2 is a right side elevation thereof;

FIG. 3 is a top plan view; and

FIG. 4 is a bottom plan view.

The left side view is a mirror image of the right side and the back is a mirror image of the front view.

I claim:

A new ornamental design for a plant transplanter, as shown and described.
